US0D1104016S

(12) **United States Design Patent** (10) Patent No.: **US D1,104,016 S**
 (45) Date of Patent: ** *Dec. 2, 2025

(54) **DISPLAY SCREEN WITH GRAPHICAL USER INTERFACE**

- (71) Applicant: **Worldpay, LLC**, Symmes Township, OH (US)
- (72) Inventor: **Manuela Dragan**, Westfield, NJ (US)
- (73) Assignee: **Worldpay, LLC**, Symmes Township, OH (US)
- (*) Notice: This patent is subject to a terminal disclaimer.
- (**) Term: **15 Years**
- (21) Appl. No.: **29/880,816**
- (22) Filed: **Jul. 27, 2023**

(57) **CLAIM**

The ornamental design for a display screen with graphical user interface as shown and described.

DESCRIPTION

The single FIGURE is a front view of a display screen with graphical user interface showing my new design. The outer broken line perimeter showing the display screen forms no part of the claimed design. The remaining broken lines show portions of the graphical user interface that form no part of the claimed design.

1 Claim, 1 Drawing Sheet
